UNITED STATES PATENT OFFICE.

JAMES BRETT, OF MATTEAWAN, NEW YORK.

IMPROVEMENT IN MANY-BARRELED-GUN BATTERIES.

Specification forming part of Letters Patent No. 42,552, dated May 3, 1861.

To all whom it may concern:

Be it known that I, JAMES BRETT, of Matteawan, in the county of Dutchess and State of New York, have invented certain new and useful Improvements in Many-Barreled-Gun Batteries; and I do hereby declare that the following is a full, clear, and exact description of the same, reference being had to the accompanying drawings, forming part of this specification, in which—

Figure 1 is a longitudinal vertical section of a battery with my improvements. Fig. 2 is a plan of the same.

Similar letters of reference indicate corresponding parts in both figures.

This invention consists in certain improved means of securing in place and of providing for the removal of the chambered breech-piece employed for the reception of the cartridges in a many-barreled-gun battery; also, in certain improvements in the mechanism for firing the charges in such a battery.

To enable others skilled in the art to make and use my invention, I will proceed to describe its construction and operation.

A is the framing of the battery, having secured across the front part of it a stout block or bar, B, which may be termed the "barrel-block," into which the barrels are to be screwed or otherwise firmly secured. This block is represented as straight; but it may be slightly curved in a horizontal direction to give a slight divergence to the barrels. In the back part of the said block there is a straight longitudinal cavity for the reception of what may be termed the "chamber-block" C, which has chambers b b bored in it for the reception of the charges, which should preferably be in cartridges, the said chambers being arranged and spaced to come exactly opposite the barrels. This chamber-block is beveled at its ends, as shown at a a in Fig. 1 in dotted lines, and may also be beveled at its top or bottom to enable it to be easily withdrawn from the said cavity. It may be constructed to load in front, and be provided in recesses in its rear with nipples for percussion-caps, or may be constructed to load in front or at the rear with fixed ammunition; but its rear face must be flat and be flush with the back of the barrel-block B when it is in place in the cavity of the said block. There

should be two or more chamber-blocks, that one or more may be loaded while another is in the barrel-block.

D is a movable breech-piece arranged behind and extending the whole length of the barrel-block B and chamber-block C. This breech-piece has its ends fitted to slide in vertical guides m in the sides of the framing, the said guides keeping the face of the said breech-piece in close contact with the back of the barrel-block and the back of the chamber-block, which is in the cavity thereof. The said breech-piece has provided in it a number of holes corresponding with the number of chambers and barrels, and arranged at corresponding distances apart for the reception of a corresponding number of pins, E E, which are all struck by one hammer, F, for the purpose of firing the charges in all the chambers simultaneously. These pins are made long enough to project some distance beyond the back of the breech-piece D, and the parts so projecting have necks c c formed in them to enter slots in a spring, G, which extends nearly the whole length of the breech-piece. This spring is represented as composed of a piece of steel-plate bent in an angular form, as shown in Fig. 1, and secured to the bottom of the breech-piece, and it is strengthened to keep it from twisting by means of a stiff strip of metal, d, which is riveted lengthwise to it. This spring serves the purpose of confining the pins E E in the holes of the breech-piece D; but it permits a longitudinal movement of the said pins when the latter are struck by the hammer F, and also serves to draw back the said pins after the hammer has been drawn back again, so that the points or front ends of the said pins may be within the breech-piece and not interfere with the vertical sliding movement of the said piece. The spring G is adjusted so that it will just draw back the pins far enough by one or more set-screws, e e, passing through the strengthening-piece d, and screwing into the breech-piece.

The hammer F consists of a strong straight bar of iron or steel arranged opposite to the chamber-block, behind the breech-piece, and fitted to slide horizontally back and forth in guides q q, provided in the sides of the framing A, and it is actuated to strike the blow by means

of two spiral springs, II, coiled round two guide-rods, ff, which are rigidly attached to the said bar F, and which slide through the transom A' of the framing, against which the said springs I I have their bearings.

J is a shaft arranged horizontally and parallel with the movable breech-piece D, in suitable bearings provided in the sides of the framing A, below the said breech-piece. This shaft carries two eccentrics, K K, for operating the breech-piece. A portion of the breech-piece is in contact with the external peripheries of the said eccentrics, and pins g in the ends of the breech-piece work in grooves h in the inner faces of the said eccentrics, as shown in Fig. 1. The shaft is turned to operate the breech-piece by means of a hand crank or lever applied to one end, which protrudes through the framing, a half-revolution of the crank and eccentrics bringing down the breech-piece from the position shown in Fig. 1 in rear of the barrel-block, in which it confines the chamber-block in place and sustains it against the recoil produced in firing, to a position below the cavity in the barrel-block to allow the chamber-block to be taken out and another one to be put in, and another half-revolution in the same or in the reverse direction returns the breech-piece to the position first mentioned. The pins E E and spring G will be understood to move with the breech-piece.

L is a horizontal shaft arranged some distance in rear of and parallel with J, in suitable bearings in the sides of the framing, and carrying two arms, M M, which serve both to draw back the hammer F for the purpose of cocking it and of liberating it to fire. The hammer is held back in the cocked position by means of two hooked levers, N N, which work on fulcrum-pins i, secured in the sides of the framing. The hooks n of the said levers are at their front ends, and the rear ends of the said levers enter the forked front ends of two levers, P P, which work on fulcrum-pins i, secured in the framing, and the rear or lower ends of which are made heavy enough to insure their always bringing down the hooks n over the front edge of the hammer, as shown in Fig. 1 in black outline, when the latter is drawn back to the cocked position. The drawing back of the hammer is effected by turning the shaft L by a lever, L', applied to one end for the purpose, in the direction of the black arrow shown near it in Fig. 1, and thus bringing the arms M M into operation against the pins k k, which are secured in two pieces, ll, which are

attached to the ends of the hammer. The liberation of the hammer to fire is effected by turning the shaft L in the direction of the red arrow shown in Fig. 1, and so bringing the arms M M into contact with and causing them to press back the loaded rear or lower ends of the levers P P, and so causing the said levers to depress the rear ends of the levers N N and raise the hooks n from the hammer, as shown in red outline in Fig. 1, leaving the latter at liberty to be driven forward by the springs I I. The hammer, when driven forward, strikes with equal force upon all the pins E E, and so causes the latter to produce the explosion of the priming. After the firing of the battery the hammer is drawn back and re-cocked by turning the shaft L in the direction of the black arrow, as hereinbefore described, the sliding breech-piece D is drawn down by a half-turn of the shaft J, and the chamber-piece C is removed and a loaded one substituted for it in the cavity of the barrel-block. The sliding breech-piece is then moved up again to its place by another half-turn of the shaft J, and the battery is ready to be fired again by simply turning the shaft L in the direction of the red arrow shown in Fig. 1.

What I claim as my invention, and desire to secure by Letters Patent, is—

1. The vertically-sliding breech-piece and chamber-block C, applied in combination with each other and with the barrel-block B, substantially as and for the purpose herein specified.
2. The spring G, applied in combination with the movable breech-piece D and with the pins E E, substantially for the purpose herein specified.
3. The combination of the single hammer F and a series of pins, E E, corresponding with the number of barrels, substantially as herein specified.
4. The combination of the hooked levers N N and loaded levers P P with each other and with the hammer F, substantially as herein set forth.
5. The shaft L and its arms M M, applied in combination with the hammer F and levers N N P P, substantially as herein described, to serve the two purposes of cocking and liberating the hammer.

JAMES BRETT.
